Primary Examiner — Shawn T Gingrich*Assistant Examiner* — Bryan N. Melvin(74) *Attorney, Agent, or Firm* — Fish & Richardson P.C.**(57) CLAIM**

The ornamental design for a coupling, as shown and described.

DESCRIPTION

FIG. 1 is a perspective view of the coupling.

FIG. 2 is a front view of the coupling of FIG. 1.

FIG. 3 is a back view of the coupling of FIG. 1.

FIG. 4 is a right side view of the coupling of FIG. 1.

FIG. 5 is a left side view of the coupling of FIG. 1.

FIG. 6 is a top view of the coupling of FIG. 1; and,

FIG. 7 is a bottom view of the coupling of FIG. 1.

The evenly dashed broken lines illustrate portions of the coupling that form no part of the claim.

1 Claim, 6 Drawing Sheets(56)
